SINK MOUNTING

Herbert D. Drain, Altadena, Calif., assignor, by mesne assignments, to Church of Religious Science, Los Angeles, Calif., a corporation of California

Application February 24, 1954, Serial No. 412,263

8 Claims. (Cl. 4—187)

This invention relates to improvements in sink mountings for installing a standard flat flange-type sink, or similar member, in an opening in a drain board, cabinet top or like supporting structure.

In modern kitchen installations where a flat flange-type sink, or similar member, is provided which is to be mounted in an opening in a drain board, cabinet top, or like supporting structure, the mounting means generally provided comprises a sealing ring or molding strip of generally T-shaped cross section, which is adapted to be positioned between the edge of the sink flange and the edge of the drain board in overlapped relation with respect to the sink flange and the top of the drain board, and a plurality of adjustable clamping members, which are adapted to be positioned beneath the sink and the drain board to rigidly secure the sealing ring in such relation as to provide a water-tight seal between the sink and the drain board. In order to facilitate the installation of the sink and to insure that the sealing strip will be properly located with reference to the sink flange, it has been found desirable to provide for initially assembling the sealing ring in proper relation to the sink flange and for connecting the same to the sink flange, so that the sink and the sealing ring may be inserted as a unit in the opening provided in the supporting structure.

It is an object of the present invention to provide a sink mounting means of the type described wherein means is provided for initially clamping the sealing ring or molding strip to the sink flange, prior to installation of the same as a unit in the aperture in the drain board.

It is another object of the invention to provide a sink mounting means of the type described and means for initially attaching the sealing strip or molding frame to the sink rim which comprises a plurality of clamping members adapted to interlock with depending portions of the molding frame adjacent the corners of the sink and to engage in frame clamping relation beneath the sink rim.

It is a more specific object of the invention to provide in a mounting means for a flat rim-type sink, or similar member, which comprises a molding frame of generally T-shaped cross section having a top portion adapted to overlie the sink rim and edge of the drain board, or cabinet top structure, in which the sink is positioned, and having a depending stem or web portion adapted to be positioned in the space between the edge of the sink rim and the edge of the opening in the drain board, a plurality of clamping devices for initially securing the molding frame to the sink rim, whereby the sink and the molding frame may be installed as a unit in the drain board or cabinet top, the clamping devices each comprising an elongate plate-like member having an adjusting screw in threaded engagement in an aperture intermediate the ends thereof and having an edge formation extending along each end thereof which is adapted to engage in interlocking relation with a shoulder formation along a lower edge of the depending stem portion of the molding frame.

These and other objects and advantages of the invention will be apparent from a consideration of the preferred form thereof which is shown by way of illustration, in the accompanying drawings, wherein:

Fig. 1 is a side elevation of the sink in inverted position and assembled with the molding frame which is attached thereto in proper relation for insertion of the sink

2

and the frame as a unit within an aperture in a supporting drain board or other member;

Fig. 2 is a bottom view, with portions broken away, of the sink installation shown in Fig. 1;

Fig. 3 is a section taken on the line 3—3 of Fig. 2, to an enlarged scale;

Fig. 4 is a bottom perspective view of the corner portion of the sink and frame showing one of the frame attaching members initially securing the molding frame to the sink rim, together with one of the clamping elements which secure the unit in final position within the aperture in the drain board;

Fig. 5 is a plan view of one of the attaching members for securing the molding frame to the sink flange;

Fig. 6 is a side elevation of the sink with the clamping frame attached, the assembled unit being shown as it is inserted in the aperture in the drain board;

Fig. 7 is a bottom plan view of the sink and molding frame completely installed in the apertured drain board and secured in final clamped position therein; and

Fig. 8 is a section, to an enlarged scale, taken on the line 8—8 of Fig. 7.

Referring to the drawings there is illustrated a sink 10 and a molding frame assembly 11 which is adapted to be attached to the sink 10 prior to its installation in the aperture 12 in a drain board 13, the sink 10 being assembled with the frame 11 and the latter being clamped to the sink flange 14 while both members are in inverted relation. Thereafter the assembled unit is inverted relative to the position shown in Fig. 1 and inserted in proper position within the drain board aperture 12.

The sink 10 is the standard type having an outwardly directed top rim or flange structure 14 and having rounded corners. The drain board 13 is a conventional linoleum covered plywood structure which may be a cabinet top or other supporting surface and which is provided with the aperture 12 of the proper size and shape to receive the sink 10 and the molding frame assembly 11.

The molding frame assembly 11 comprises a sealing ring or molding frame member 15 of one-piece construction, preferably of extruded metal, which is adapted to be positioned around the periphery of the sink flange 14 with one side or top portion 16 overlying the top surface of the sink flange 14 and with the other side or top portion 17 extending in overlying relation to the adjoining top surface of the drain board 13. The sealing ring 15 includes a depending web or stem portion 18 which is adapted to be positioned in the space between the outer edge of the sink flange 14 and the edge of the drain board 13 which surrounds the aperture 12. The sealing ring web or flange 18 is provided along its lower inner edge with an inwardly extending thickened portion or shoulder formation 19 having a bottom face 20, an inner face or side edge 21 and a top face or edge 22, the latter extending at a slight angle downwardly towards the main portion of the web 18 so that an upwardly facing hook-like formation is provided along the bottom edge of the web 18. The depth of the web 18 is sufficient to bring the bottom edge 20 approximately on the level with the bottom edge of the drain board 13 in which the sink is mounted and below the bottom surface of the rim 14 of the sink 10.

When installing the sink 10 in the drain board 13 it is desirable, particularly in the case of cabinet tops, to be able to first attach the sealing strip or molding frame 15 to the flange or rim 14 of the sink 10 with the sink 10 and the sealing strip 15 in the inverted position with respect to the final location of the same in the drain board 13 so that the sink 10 and the sealing strip 15 may be properly located with respect to each other, and the sealing strip 15 may be readily clamped to the sink flange 14 to retain the same in the proper relation to the sink and to permit the insertion of the sink 10 and the sealing strip 15 as a unit.

A plurality of molding frame attaching or clamping members 23 (Fig. 5) are provided for initially attaching the molding frame 15 to the sink flange 14. The attaching members 23 each comprise a metal plate or strip cut to the shape shown in Fig. 5 and having the opposite end edges 24 and 25 extending in right angle

relation to each other. The end edges 24 and 25 are bent or shaped to provide hook-like flanges 24', 25' which are adapted to interlock with the hook-like shoulder formation 19 on the inner end of the web 18 of the molding frame 15. A threaded aperture 26 is provided intermediate the ends of the plate member 23 for receiving the clamping screw 27. Four of the attaching members 23 are adapted to be positioned on the frame member 15, one at each of the four corners of the sink 10 with the end flange formations 24', 25' in interlocking engagement with the shoulder formation 19 on the web 18 of the frame member 15, and to be clamped in fixed relation thereto by taking up on the screw 27 which engages at its inner end beneath the flange 14 of the sink 10.

After the sink 10 and the molding frame 15 are connected the resulting unit is positioned in the aperture 12 in the drain board 13 as shown in Fig. 6. Thereafter, a plurality of clamping elements 30 are arranged in spaced relation around the periphery of the sink flange 14 for securing the molding strip 15, the sink 10, and the drain board 13 in assembled relation.

The clamping elements 30 each comprise a generally rectangular plate or body portion 31 having at one end thereof a threaded aperture 32 and a clamping screw 33 which is adjustably secured therein. Intermediate the ends of the plate portion 31 there is provided an upstanding hook-like formation 34, the undersurface 35 of the hooked end of which is beveled, or downwardly sloping, for cooperation with the top surface 22 of the shoulder 19 on the bottom of the web 18 of the molding frame 15. The clamping elements 30 are arranged with the opposite end of the plate portion 31 extending beneath the drain board 13 and flange 14 of the sink 10 as illustrated in Figs. 4 and 8. The hook or groove formations 34 on the clamping elements 30 are so constructed that the elements pivot about the shoulder or rim 19 on the bottom of the web 18 when engaged therewith. The apertured end of each of the elements 30 extends beneath the flange 11 of the sink 10 and the opposite end extends beneath the drain board 13.

After the elements 30 are properly positioned in engagement with frame 15 the adjusting screws 33 are taken up to clamp the elements in position. The screws 33 tend to force the flange 14 into snug relation with the inner top portion 16 of the sealing ring 15 and also to force the opposite ends of the elements 30 into clamping relation with the bottom of the drain board 13 and the outer top portion 17 of the molding strip 14 into tight engagement with the top of the drain board 13. The molding frame 15, together with the frame attaching and clamping members 23 and 30 may be provided as a kit for use when the sink 10 is installed in the aperture 12 of the drain board 13. The kit permits the molding frame to be initially assembled with the sink and the assembled unit to be readily installed, either in the shop, or in the field, greatly facilitating the installation of the sink in either location.

While specific details of construction have been referred to in describing the illustrated form of the invention it will be understood that other details may be resorted to within the spirit of the same. Also, the mounting herein disclosed may be employed for securing in an apertured support a range unit or other member having a flanged edge or rim of the same general character as the flange of the sink illustrated.

I claim:

1. Means for initially holding a peripherally rimmed member within a mounting frame to permit insertion of the member and frame as a unit in an opening in a generally, flat supporting structure, said mounting frame being characterized by a top portion which is adapted to overlie both the rim of the member and the edge of the opening in the supporting structure and a web portion which is adapted to extend between said rim and edge, the web portion being provided adjacent its lower edge with an inwardly directed shoulder formation, which shoulder formation includes an abutment surface which faces in the direction of the top portion of said frame and which is spaced a substantial distance from said rim, said holding means comprising a plurality of holding devices for coaction with the rim of the member and the web portion of the frame, each of said holding devices consisting of a rigid element which is adapted to extend across a corner of said rim between two adjoining

web portions of said frame, said element being adapted to be positioned with its ends engaging the abutment forming surfaces of said web portions, and a screw carried by an intermediate portion of said element for adjustable clamping engagement with the underside of the rim of the member.

2. Means for initially holding a peripherally rimmed member within a mounting frame to permit insertion of the member and frame as a unit in an opening in a generally flat supporting structure, said mounting frame being characterized by a top portion which is adapted to overlie both the rim of the member and the edge of the opening in the supporting structure and a web portion which is adapted to extend between said rim and edge, said web portion having adjacent its lower edge an inwardly directed abutment forming ledge which faces in the direction of the top portion of said frame and which is spaced a substantial distance from said rim, said holding means comprising a plurality of holding devices for coaction with the rim of the member and the web portion of the frame, each of said holding devices consisting of a clamp plate adapted to extend across a corner of said rim between two adjoining web portions at a corner of said frame, said clamp plate having its ends in engagement with the frame between the abutment forming ledge and the top portion of the frame, and a clamping screw carried by an intermediate portion of said clamp plate for adjustable clamping engagement with the underside of the rim of the member.

3. Means for holding a member having a generally flat peripheral rim within a mounting frame to permit downward insertion of the member and the mounting frame as a unit into an opening in a generally flat horizontal supporting structure, said mounting frame being of generally T-shaped cross section and having a top portion which is adapted to overlie both the rim of the member and the edge of the opening, and a vertical web portion which is adapted to extend downwardly between said rim and edge, said means comprising corner holding devices for coacting with the rim of the member and the web portion of the mounting frame, each of said holding devices consisting of a rigid element which is spaced below the top portion of the mounting frame for a distance greater than the thickness of the rim of the member for coaction with the lower part of the web portion of said mounting frame and which is adapted to extend below said rim and across a corner of said mounting frame between angularly related web portions thereof, complementary locking formations on the web portions adjacent the lower edges thereof and on each element adjacent the end edges thereof, which formations interlock with each other to secure each element to the lower part of the web portions, and a screw mounted in and projecting upwardly of each element for adjustable clamped engagement with the rim of the member.

4. A mounting for positioning a generally rectangular flange-type sink in an apertured supporting structure comprising a mounting frame having a top portion adapted to extend laterally over the top surface of the sink flange and the adjacent edge of the supporting structure and a stem portion adapted to depend between the sink flange and the edge of the supporting structure, said stem portion having an upwardly directed hook-like shoulder formation adjacent the bottom edge thereof projecting inwardly of the stem portion toward the sink and fastening elements for securing the frame to the sink flange, said fastening elements being positioned at the corners of the frame beneath the sink flange and extending across the corners of the sink flange when the frame is positioned on the sink flange, said fastening elements having marginal end portions adapted to be positioned in interlocking engagement with said hook-like shoulder formation on the frame, said fastening elements having a threaded screw receiving aperture intermediate the ends thereof, and a screw in said aperture with the end thereof in abutting engagement with the bottom surface of the sink flange whereby to lock said frame in position on the sink for installation of the sink and frame as a unit.

5. Means for initially holding a peripherally rimmed member within a surrounding frame to permit insertion of the member and frame as a unit in an opening in a generally flat supporting structure, comprising the combination with a mounting frame having a top portion which

is adapted to overlie both the rim of the member and the edge of the opening in the supporting structure and a web portion which is adapted to extend a substantial distance below said rim and between said rim and edge, of a plurality of holding devices for coaction with the rim of the member and the web portion of the frame, each of said holding devices consisting of an element which is formed to extend across a corner of said rim between two adjoining web portions at a corner of said frame, interengaging means on the ends of said element and the web portions of said frame, and a clamping member carried by an intermediate portion of said element for adjustable clamping engagement with the underside of the rim of the member.

6. A mounting for positioning a generally rectangular peripherally flanged member in an apertured supporting structure comprising a mounting frame having a top portion adapted to extend laterally over the top surface of the flange of the member and the adjacent edge of the supporting structure and a stem portion adapted to depend between said flange and the edge of the supporting structure, said stem portion having a shoulder formation adjacent the bottom edge of said stem portion and fastening elements for securing the frame to said flange, said fastening elements being positioned at the corners of the frame beneath said flange and extending across the corners of said flange when the frame is positioned on the member, said fastening elements having marginal end portions adapted to be positioned in interlocking engagement with said shoulder formation on the frame, and said fastening elements having an adjustable clamping element intermediate the ends thereof positioned for abutting engagement with the bottom surface of said flange whereby to lock said frame in position on the member for installation of the member and frame as a unit.

7. Means for initially holding a peripherally rimmed member within a mounting frame to permit insertion of the member and frame as a unit in an opening in a generally flat supporting structure, said mounting frame being characterized by a top portion which is adapted to overlie both the rim of the member and the edge of the opening in the supporting structure and a web portion which is adapted to extend between said rim and edge, the web portion being provided adjacent its lower

edge with a shoulder formation, which shoulder formation includes an abutment surface which faces in the direction of the top portion of said frame and which is spaced a substantial distance from said rim, said holding means comprising a plurality of holding devices for coaction with the rim of the member and the web portion of the frame, each of said holding devices consisting of a rigid plate-like element which is adapted to extend across a corner of said rim between two adjoining web portions of said frame, said element being adapted to be positioned with its ends engaging the abutment forming surfaces of said web portions and a member carried by an intermediate portion of said element for adjustable clamping engagement with the underside of the rim of the member.

8. Means for holding a member having a generally flat peripheral rim within a mounting frame to permit downward insertion of the member and the mounting frame as a unit into an opening in a generally flat horizontal supporting structure, said mounting frame being of generally T-shaped cross section and having a top portion, which is adapted to overlie both the rim of the member and the edge of the opening, and a vertical web portion which is adapted to extend downwardly between said rim and edge and which is provided at its bottom edge with an inwardly facing shoulder formation, said holding means comprising corner holding devices for coacting with the rim of the member and the web portion of the mounting frame, each of said holding devices consisting of a rigid plate-like element which is spaced below the top portion of the mounting frame for a distance greater than the thickness of the rim of the member for coaction with the shoulder formation on the web portion of said mounting frame and which is adapted to extend below said rim and across a corner of said mounting frame between angularly related web portions thereof, complementary locking formations on the shoulder formation of the web and on the end edges of each element, which formations interlock with each other to secure each element to the web and a screw mounted in and projecting upwardly of each element for adjustable clamped engagement with the rim of the member.
